(57) **CLAIM**

The ornamental design for a container body portion, as shown and described.

DESCRIPTION

FIG. 1 is a top-front-left perspective view of a container body portion showing an embodiment of the claimed design; FIG. 2 is a front elevational view of FIG. 1; FIG. 3 is a rear elevational view of FIG. 1; FIG. 4 is a right side elevational view of FIG. 1; FIG. 5 is a left side elevational view of FIG. 1; FIG. 6 is a top plan view of FIG. 1; and, FIG. 7 is a bottom plan view of FIG. 1. The broken lines shown in the drawings illustrate portions of the container body portion that form no part of the claimed design.
